Inventor:

UNITED STATES PATENT OFFICE.

LOUIS SEKOFSKY, OF SAN FRANCISCO, CALIFORNIA.

FOLDING BED.

SPECIFICATION forming part of Letters Patent No. 473,355, dated April 19, 1892.

Application filed May 23, 1891. Serial No. 393,850. (No model.)

To all whom it may concern:

Be it known that I, LOUIS SEKOFSKY, a citizen of the United States, residing in the city and county of San Francisco, and State of

5 California, have invented certain Improvements in a Combined Folding Bed and Cabinet-Furniture; and I hereby declare the following specification and drawings to be a full, true, and exact description of the same.

10 My invention relates to beds that are concealed or disguised when not in use, and combined with other cabinet-furniture so that the floor-space occupied will be available for double use without in any important way 15 modifying either the bed or the cabinet-furniture so connected by reason of their being combined together.

My invention consists in a rectangular case of such form and dimensions as will receive 20 a common bed when the latter is in a vertical position and in hinging to the front of this case any common form of cabinet-furniture that can have like dimensions with the central or main case, such articles of cabinet-furniture swinging each way, after the manner 25 of doors, completely concealing the bed when closed, but in no way modified so as to indicate other than permanent use of their purpose in concealing the bed.

30 It also consists in the method of mounting and hinging the bed to the main case so that the former can be readily removed and require but little, if any, modification for this particular use, as set forth and more fully explained 35 in the accompanying drawings, forming a part of this specification.

Similar letters of reference are employed to designate corresponding parts in the different figures.

40 Figure 1 is a front elevation of one of my improved folding beds combined with a wardrobe on one side and a cabinet-case on the other side, the latter containing various compartments adapted for toilet or other purposes. Fig. 2 is a vertical section through Fig. 1 on the line xx . Fig. 3 is also a vertical section through Fig. 1, showing the bed in position for use and the hinged cabinet-cases thrown back out of the way. Fig. 4 is a plan 45 section on line yy of Figs. 1, 2, and 3, showing the position of the bed when in use and also that of the hinged cabinet-cases

when partially or wholly swung clear of the bed. Fig. 5 shows details of the method of hinging the bed to the main case and providing for its removal. 55

Referring to the drawings, the main case for containing the bed B is preferably formed of three sections, consisting of central rectangular part A, a base C, and a top part F. The central or main part A is rectangular in shape and large enough to contain a bed B of any common form, the top or head projecting downward in the base portion C when the bed is folded or raised, as shown in Fig. 2. The bed B is hinged 60 to the base or lower section C of the main case, as shown in Figs. 2 and 3 and also in the enlarged detail, Fig. 5.

The upright or folded position of the bed B is shown in Fig. 2, in which position the hinge D is held by gravity and, as may be seen, the bed can be readily lifted out, the hinge D separating in any position or angle as low as that indicated in Fig. 5. The hinge D consists, essentially, of a bolt having a 75 curved or finger-like projecting end, which bolt is secured by screws or other suitable means to the bed, and is arranged so that the finger-like end thereof can loosely engage an eye-plate or strap secured rigidly to the lower 80 base C.

To counterbalance the bed B so that it can be easily raised from the position shown in Fig. 3 to that in Fig. 2, I attach at the end a weight E, which can be of such proportions as will 85 cause the bed to rise or fold with a few pounds of effort. This is, however, a common expedient, which I do not claim as new.

To render the case portable and convenient to handle and erect, I construct it in three detachable parts, consisting of the base C, the main or central part A, and the top part F, these being joined in the usual manner by screws, tenons, and keys, or in any manner to make a strong joint between the several 95 parts. When the bed B is lowered, the pivoted support G falls into the position shown in Fig. 3, and when the bed is raised or folded this support returns to the position shown in dotted lines at Fig. 2. This bed B, as may be 100 seen, when thus mounted does not require modification from the common form, but can be made with woven wire, as shown in Fig. 4, or in any other manner preferred, because

the bottom is covered and concealed by other and different parts, as will now be explained.

Between the top F and the base C, I attach by hinges to the main part A two cabinet-

- 5 cases M and N, as shown in the front elevation, Fig. 1, and the plan view, Fig. 4, and also in edge view at Fig. 2. These cases are made in such manner as to be safely supported from one corner when filled with goods of 10 any kind. These cases are modified to suit the requirements in any case. In a room other than a bed-room—a library, office, or parlor, for example—the cabinet-cases can be for books, filing papers, or other purposes. For 15 a bed-room I make, preferably, a wardrobe of the case N, provided with hooks and shelves inside and a mirror in the door. At the other side the case M is provided with a desk, as shown at H, Figs. 1 and 2; also, open cases at 20 L L and a locker I.

At O and R, I provide drawers for clothing, and also in the base C of the main structure I arrange two drawers P and Q to contain either personal effects or clothing for the bed 25 B, as may be required.

It is obvious that the purposes and uses of the two cabinet-cases M and N can be varied in any manner, as taste or the requirements of use may demand, so long as they are 30 mounted to swing into the positions as shown in the drawings.

In case it is desirable to partially inclose the bed B these covers can be set in the position indicated by dotted lines at S and S, Fig. 4.

35

Having thus described the nature and objects of my invention and the method of applying the same, what I claim as new, and desire to secure by Letters Patent, is—

In a folding bed, the combination of the 40 central rectangular section A, the base C, on which it is mounted, the bed B, arranged vertically within the sections A and C and pivoted removably to the section C, the top F of the cabinet, the hinged cabinet-cases M and 45 N, arranged between the top F and the base C alongside of the section A, said case M being provided with a desk H, open cases L L, and locker I, and the horizontal drawers O and R in the lower ends, respectively, of the 50 cases M and N, together with the drawers P and Q, located within the case C, all the parts being arranged to operate substantially in the manner and for the purpose specified.

In testimony whereof I have hereunto 55 affixed my signature in the presence of two witnesses.

LOUIS SEKOFSKY.
